UNITED STATES PATENT OFFICE.

WILLIAM J. TURNER, OF SEEKONK, MASSACHUSETTS.

TRAP.

Application filed July 31, 1919, Serial No. 314,539. Renewed October 10, 1922. Serial No. 593,656.

To all whom it may concern:

Be it known that I, WILLIAM J. TURNER, a citizen of the United States, residing at Seekonk, in the county of Bristol and State 5 of Massachusetts, have invented certain new and useful Improvements in Traps, of which the following is a specification.

This invention relates to improvements in steam traps and, more particularly, to all- 10 metal traps. It is among the objects of the invention to provide a trap which shall be practicable of manufacture by ordinary machine operations; be capable of use against relatively high pressure as well as extremely 15 low; have few and simple parts; have those parts interchangeable for different adjustments, and to a large degree interchangeable for different sizes; and in general combine the foregoing attributes with the other 20 advantages of the invention herein described, in apparatus which is strong, reliable, and relatively inexpensive. As a result, in addition to obvious advantages of low cost, reliable operation, and convenience, the apparatus 25 of the invention has a special commercial utility on account of the relatively small number of parts that need be carried in stock by one having on hand a full line of sizes.

30 The object in general being to provide an automatic valve which shall permit the escape of air but not the escape of steam, or, in case of any fluid, to operate as a shut off on the attainment of a predetermined tem- 35 perature, the principle of differential expansion of relatively large metallic tubes is used to apply great power to the short arm of a lever whose long arm, also tubular and extending parallel to the said tubes, is a 40 beam of great strength acting directly upon the valve.

While the invention may be embodied in apparatus in various forms, reference is made to the accompanying drawings as 45 showing a peculiarly simple and desirable form. It is intended that the patent shall cover, by suitable expression in the appended claims, whatever features of patentable novelty exist in the invention disclosed.

50 In the accompanying drawings:

Figure 1 is a front elevation of an embodiment of the invention, in medial section;

Figure 2 is a plan of the same in section on the line 2-2 of Figure 1;

Figure 3 is a side elevation of a part of 55 the same in section on the line 3-3 of Figure 1; and

Figure 4 is a perspective of a detail.

Referring to the drawings, 10 indicates the cylindrical part of a casing adapted to 60 discharge through its lower end 11 whatever fluid enters it through the valve 12 in tubular plug 13, from the pipe, radiator, or other apparatus to which it is attached. The said valve 12, mounted in the plug 13, tends to 65 stand open, being pressed away from its seat 12' by a spring 14 which is strung around the stem 15 of the valve and presses from a shoulder 7 within the tube, adjacent to the valve seat, through the medium of fluted 70 washers 16 which center the said valve stem within the passage 17. One of these is seated against said shoulder and the other against a pin or shoulder 8 on the stem. The valve can, however, be seated by pressure of the tubular beam 18 on the end of its stem 15. This beam forms a part of the 75 long arm of a lever which is swung to the left, as the parts are represented in Figure 1, whenever the point 19, which may be taken 80 as the point of application of power to the lever, rises with respect to the knife edge 20 which may be taken as the fulcrum. The thermostatic elements and the beam are all 85 nested together in parallelism, very compactly and with great power and strength, as follows: The casing 10 is a tubular piece, preferably made of cast iron and extending 90 preferably upward, from the plug 13 by which it is attached to the apparatus with 95 which it is to work. It is closed at its top by a tubular screw threaded plug 21 which thus constitutes the end wall of the casing, the tube of which plug is in turn closed by 100 a tubular screw plug or sleeve 22, whose axial opening is in turn closed by a pin 23 whose head is within, has a shoulder 24 bearing upward against the inner end of this tubular plug 22, and carries the ridge with 105 knife edge 20 that points downward and constitutes the fulcrum. When the parts are assembled, this fulcrum is fixed in position within the casing, being barred against any upward movement with respect to the 110 casing 10 by the screw engagements of the plugs 22 and 21, the former of which is set down against the shoulder 24 of the pin, and being barred against any downward move-

ment by the lever, composed of the plug 25 and the tubular beam 18. This plug closes the end of this tubular beam and has a notch 20' to receive and co-operate with the fulcrum edge 20. The lever is of the bell crank type, although not at all resembling such in aspect, in that the power, as illustrated, is applied vertically while the beam swings horizontally. The application of power is by the ridge and knife edge 19 on top of the bronze expansion post 9 pressing upward in the notch 19' on the under side of the plug 25 at a short distance from the plane of the fulcrum knife edge. The "point" of application of the power may be considered either as the point of a cone, or as the crest of a ridge, the former being somewhat cheaper in manufacture, and the latter more durable in use. If the latter form be chosen, the crest or knife edge 19, and the notch 19' in which it is seated, will be parallel to the edge and notch 20, 21', of the fulcrum. The plane of each is indicated in Figure 1 by the dot and dash lines 20" and 19" extending vertically rather close together in the middle of the figure, the distance between which is the length of the short arm of the lever.

With this description of structure and function of what is herein referred to as constituting the bell crank lever, it will be understood that the tube 18 and its plug 25 together constitute the lever, and that the short arm of the lever is that part of the plug 25 which lies between the lines 19" and 20", that is, between the point of application of the power and the fulcrum, and that the long arm of the lever, sometimes referred to as the tubular arm or the beam, is the tube 18, extending from the fulcrum to the point of engaging the resistance, where this tube engages the valve stem 15.

The power is applied by the expansion post 9, made of brass or other metal having a co-efficient of expansion greater than that of the casing 10. This post is preferably tubular and rests at its bottom on a pin 29 which crosses through the middle of the tubular casing 10. For the stronger holding of this pin, bosses 30 may be provided, projecting inward in the casing, and serving also to centre the lower end of the expansion post within the tube, in the direction which is toward and from the eye in Figure 1. By a semi-circular notch 29' formed in its bottom end, the expansion post 9 straddles the pin 29 so as to prevent any displacement of the lower end of the post in the direction which is toward the right or left in Figure 1. The post can, however, swing on this pin as on a pivot the trifling degree needed for its top to fit plugs having greater or less distance between the planes of power application and of fulcrum 19" and 20".

These several tubular elements are substantially concentric. The power and fulcrum bearings are fixed in relation to each other, because they are made on a single plug that fills one end of the tubular beam. The top 70 of the beam 18 is maintained central in the casing by the joint effect of the fulcrum notch and the flat side walls 34 of the interior of the casing 10, provided at that point of suitable dimension to receive and 75 centre the top end of the beam 18 in the direction which is toward or from the eye in Figure 1.

In operation, the apparatus is to be set so that the valve 12 will be held open by its 80 spring 14 when the temperature is below that at which the apparatus is to operate, but so that at the predetermined temperature the length of the post 9 will have increased enough more than the length of the 85 casing 10 has increased to have raised the point 19, with respect to the fulcrum 20, so as to swing the tubular lever beam 18 to the left, as the parts are viewed in Figure 1, enough to drive the valve stem 15 and valve 90 12 to a seated position.

In order to adjust the valve for any installation, the plug 22 at the top may be screwed upward, thus raising the fulcrum, and letting valve 12 open. Steam may be 95 allowed to pass freely through the apparatus until the same is thoroughly heated to the temperature at which it is desired to have the apparatus automatically close the valve 12. Then the plug 22 may be screwed down 100 tight until the valve 12 is closed so that no steam escapes, and secured by a lock nut if desired. The conditions within may be observed by use of a test valve 35, provided 105 in the casing near the bottom.

When in operation, as condensation accumulates and the apparatus cools, the expansion post 9 contracts and the valve 12 is opened by the pressure of steam behind it or by its spring 14. Condensation is then discharged until steam again comes to and passes through the valve 12, heats the expansion post 9 and causes the valve 12 to close. Speed of action is enhanced by the provision of vent or circulation holes 26, in 110 the upper part of the tubular beam, and 26' in the upper part of the tubular expansion post, both of these tubes being open at their lower ends.

The lever beam 18 being tubular and large 115 is very strong and can therefore close the valve 12 and hold it closed against a very high steam pressure. It is, however, desirable to use a smaller valve 12 with the higher steam pressures.

The construction described makes the trap adaptable to a wide range of pressures, from sub-atmospheric or "vapor" up to two hundred pounds or more. The size of valve opening 12' and the short arm of the lever 125 130

can each be readily changed, each being in a separate plug for which another with a different size valve opening, or length of arm, can be substituted. As illustrated, 5 both the valve seat plug 12" and the valve 12 would be changed, to change the valve, the new ones being inserted in the same plug 13; while if the valve 12 were made with a conical, convex or hemispherical head, instead 10 of with the irregular shape illustrated, it would be necessary only to change the valve seat plug 12". Therefore, it is not necessary for a dealer, in commercial practice, to keep a large number of varieties in stock, 15 for any variety that may be specified for a casing of given size can be made by an ordinary workman by putting in the proper screw plugs. Although the short arm of the lever is such a small fraction of an inch in 20 actual measurement, the location of its bearings points in the plug 25 can readily be made by precision machinery with sufficient accuracy; and although the edges are spoken of as a "knife edge" it will be understood 25 that for practical purposes the "knife" edge will usually be made with an appreciable thickness, to resist wear. Adjustment can easily be made for any wear that may occur by means of the screw settings. The 30 fulcrum knife edge may always accommodate itself to a new setting, because of the slip connection between the head which carries it and the adjusting plug 21 which rotates to screw it downward, the fulcrum 35 knife edge being in effect set on a swivel. This is therefore, in the claims, said to be "swivelled", in the tubular "screw plug" 21 which closes the tubular casing 10, being mounted in and shouldered rotatably on the 40 "screw sleeve" 22 which is within said plug. The seat of the valve 12 can be easily cleaned by disconnecting the parts, being removable; and this feature is of special value 45 in washing out a new job because this valve seat can be left out until sediment has all been blown through.

The invention thus disclosed provides a trap of such simple and substantial mechanical parts and of such strength and 50 range of leverage and of valve sizes that the principle can be applied to traps for radiators and low pressure heating and also to mills, engine rooms, drying apparatus, and the like where high pressure and super-heated steam are required; and the trap can be set and adjusted while under working pressure.

In the claims, the term "expansion post" 55 is used for brevity, and it will be understood that this refers to differential expansion in comparison with the tubular casing in which it is contained. In so far as both the casing and the post expand an equal distance, there is no effect, and it is the additional

expansion which the post undergoes which 65 makes the apparatus operative.

By mounting the expansion post pivotally and using a knife edge for its lever contact, it is possible to use the same expansion member with various plugs 25 substituted for 70 each other in the same lever, each with fulcrum groove 20' offset to a different distance from the diametrically arranged groove 19', thus making the short arm of 75 the lever of differing lengths. As the fulcrum 20 is in a diametric plane through the casing 10, the plug 25 and with it the top of the expansion post is offset from the middle of the casing more or less, according to the distance between the planes of the fulcrum groove 20' and the expansion post groove 19'; while the support 29 of that post never moves, and must always afford a firm and steady support. The pivotal support for 80 the bottom end of the expansion post and the use of knife edges at the top makes possible a ready accommodation for the differing angles as different plugs are substituted. By making the plug 25 with a long 85 body and with a shoulder 25' fitting against a machined upper end of the tubular lever 18, a connection between the plug and the lever is made which provides tightness notwithstanding there may be some looseness or 90 lost motion in the screw connection. Such tightness is a matter of importance where the short arm is, for example, only three or four sixty-fourths of an inch in length. Assuming that the leverage of the tubular lever 95 is approximately 200 to 1 and that the valve 12 is working against a pressure so high that there is ten pounds push against this valve, there will be two thousand pounds push on the expansion post. The invention, 100 however, provides a design of such strength that the metals and the contact points can easily be made to stand and transmit several times this ton of pressure; and in this connection the value of having a tight fit of 105 the shoulder 25' of the plug to prevent any lost motion notwithstanding the possible looseness of the screw becomes manifest. It 110 is a further advantage of the invention that the tube 18 is adapted to work against the valve on its every side. It would be difficult to arrange its screw thread so as to make a particular part of the tube come to rest just opposite the valve when the tube 18 is 115 screwed to reach a tight fit against the shoulder 25' of the plug. This adaptability is due to the circular character of the valve-engaged part of the tube. The making 120 of a rim of enlarged thickness of this part of the tube, which can be turned smooth and uniform, is another feature tending to make the apparatus an instrument of precision. The feature by which the fulcrum 20 is swivelled, and at the same time is adjustable to varying distances axially toward the

expansion post by the screw plug 22, is another advantageous feature. It permits the use of a knife edge fulcrum in which the heavy stress is distributed over a considerable length of line, and yet permits the fulcrum to be screwed down tight without its alignment being disturbed. To this end, a lubricant may be employed between the screw tubular plug 22 and the shoulder of 10 the head 24 carrying the fulcrum 20 if ever found advisable.

I claim as my invention:

1. A trap, comprising in combination a metallic tubular casing having an entrance valve and an open discharge; an expansion post and a bell-crank lever in the casing, the bell-crank being fulcrumed on the casing, engaging the expansion post at a short distance transversely of the casing from the 15 fulcrum, lying alongside of the expansion post and engaging the valve at a relatively considerable distance lengthwise of the casing.
2. A trap, comprising in combination a metallic tubular casing having an entrance valve and an open discharge; a tubular expansion post and a bell-crank lever in the casing, the bell-crank being fulcrumed on the casing, engaging the expansion post a 20 short distance transversely of the casing from the fulcrum; and engaging the valve at a relatively considerable distance lengthwise of the casing.
3. A trap, comprising in combination a metallic tubular casing having an entrance valve and an open discharge; an expansion post and a bell-crank lever in the casing, the bell-crank being fulcrumed on the casing, engaging the expansion post at a short distance 25 transversely of the casing from the fulcrum, and having a tubular arm engaging the valve at a relatively considerable distance lengthwise of the casing.
4. A trap, comprising in combination a metallic tubular casing having an entrance valve and an open discharge; an expansion post and a bell-crank lever in the casing, the bell-crank being fulcrumed on the casing, engaging the expansion post at a short distance 30 transversely of the casing from the fulcrum, and engaging the valve at a relatively considerable distance lengthwise of the casing; the said casing, the valve-engaging part of the bell-crank, and the expansion post being tubes nested together.

5. A trap, comprising in combination a metallic tubular casing having an entrance valve and an open discharge; an expansion post and a bell-crank lever in the casing, the bell-crank being fulcrumed on the casing, engaging the expansion post at a short distance 35 transversely of the casing from the fulcrum, and engaging the valve at a relatively considerable distance lengthwise of the casing; the said casing, the valve-engaging part of the bell-crank, and the expansion post being tubes nested together.

gaging part of the bell-crank, and the expansion post being tubes nested together; there being openings providing circulation through the valve-engaging tube into the expansion post close to the fulcrum.

6. A trap, comprising in combination a metallic tubular casing having an entrance valve and an open discharge; a plug, closing one end of the tubular casing adapted to engage a lever as a fulcrum and adjustable in position with respect to the casing; a bell-crank lever fulcrumed thereon within the casing; and an expansion post supported at the other end of the casing and engaging the short arm of the lever at the fulcrum end of the casing; the long arm of the lever engaging the valve at the other end of the casing.

7. A trap, comprising in combination a metallic tubular casing having an entrance valve and an open discharge; a screw plug closing one end of the tubular casing and having swivelled in it a member adapted to engage a lever as a fulcrum; a bell-crank lever fulcrumed thereon within the casing; an expansion post within the casing; the short arm of the lever engaging said post and the long arm of the lever engaging the valve at the other end of the casing.

8. A trap, comprising in combination a metallic tubular casing having an entrance valve and an open discharge; a tubular screw plug closing one end of the casing; a screw sleeve within said tubular plug; and a shaft filling the sleeve, having a head within the casing shouldered on the inner end of said sleeve and adapted to engage a lever as a fulcrum; a bell-crank lever fulcrumed thereon within the casing; an expansion post within the casing; the short arm of the lever engaging said post and the long arm of the lever engaging the valve at the other end of the casing.

9. A trap, comprising in combination, a metallic tubular casing having an entrance valve and an open discharge; an expansion post within the casing; a tube within the casing, surrounding the expansion post, adapted to be swung laterally, and to engage the valve when so swung; and means whereby the tube engages with the casing as a fulcrum, and is swung laterally by expansion of said post.

10. A trap, comprising in combination a metallic tubular casing having an entrance valve and an open discharge; an expansion post within the casing; a tube within the casing, surrounding the expansion post, adapted to be swung laterally, and to engage the valve when so swung; and a plug in said tube engaging the expansion post within the tube, and engaging the casing outside of the tube with the line of stress through one of these engaging points passing close beside but not through the other of said engaging

- points, whereby expansion of the post swings the tube.
11. A trap, comprising in combination a metallic tubular casing having an entrance valve and an open discharge; an expansion post within the casing; a bell-crank lever in the casing; and a plug in the end of the casing carrying a knife edge fulcrum; said bell-crank lever being engaged by the expansion post, fulcrumed on said fulcrum close thereto, and engaging said valve at a distance from said fulcrum.
12. A trap, comprising in combination a casing having an entrance valve and an open discharge; a bell-crank valve lever in and fulcrumed on the casing, comprising a plugged tube; and an expansion post within said tube; the plug of the tube having a knife edge engagement with the post.
13. A trap comprising, in combination with a valve, two differentially expanding stout straight metallic tubes; and a lever whose short arm length is fixed by close-together knife edge engagements with said tubes and whose long arm extends parallel to the tubes and acts directly on the valve.
14. A trap, comprising in combination a casing having an entrance valve and an open discharge; a simple lever having a long arm controlling the valve and a short transverse arm; and an expansion post parallel to the long arm and actuating the short arm.
15. A trap, comprising in combination a metallic tubular casing having an entrance valve and an open discharge; a bell-crank lever having a tubular long arm; and an expansion post; all being nested together and there being flat sided interior opposite surfaces on walls of the casing centering one of the inner members while permitting it motion parallel to said flat sided walls.
16. A trap, comprising in combination a metallic tubular casing having an entrance valve and an open discharge; a pin passing transversely through the casing; an expansion post within the casing, based on said pin; and a lever engaged by the top of said expansion post, fulcrumed on the casing, and controlling the valve.
17. A trap, comprising in combination a casing having an entrance valve and an open discharge; an expansion post within the casing; and a lever controlling the valve, fulcrumed on the casing, and engaged by said expansion post; there being a single part of the lever containing the fulcrum and expansion post engagement, which has fixed points for such engagements and is removable for substitution of a similar part having differently fixed points.
18. A trap, comprising in combination a metallic tubular casing having an entrance valve and an open discharge; an expansion post and a tubular lever nested therein; a fulcrum for the lever, movable in position on the casing; and a testing valve arranged in an opening through the casing near the level of the entrance valve.
19. A trap, comprising in combination a casing having an entrance tube, and an open discharge; a simple lever, and an expansion post engaging the short arm thereof; the said short arm being in a removable piece of the lever for which a piece with a different length of short arm may be substituted; and the seat of said valve being in a removable piece for which a piece with valve seat of different size may be substituted.
20. A trap, comprising in combination a casing having an entrance valve and an open discharge; a lever controlling the valve and an expansion post actuating the lever; there being a removable tubular plug containing said valve, having fluted washers guiding the stem of the valve, of which washers one bears against a shoulder in the plug and the other against a shoulder on the valve stem, and a spring between and tending to separate said washers and thus to open said valve.
21. A trap, comprising in combination a metallic tubular casing closed at one end, open at the other end, and having a side entrance with valve near its open end; an expansion post within, extending from near said open end to near said closed end; and a simple lever engaged between the post and the closed end of the casing and having a long arm extending from said closed end to said valve.
22. A trap having, in combination with a valve and an expansion member, a lever intervening, comprising a tube which in the direction of its axis constitutes the long arm of the lever; the other arm being in direction transverse of the tube.
23. A trap having, in combination with a valve and an expansion member, a lever connecting them, comprising a tube which in the direction of its axis constitutes the long arm of the lever; the valve engaging end of said arm being adapted to engage the valve at any point in its circumference.
24. A trap having, in combination with a valve and an expansion member, a lever connecting them, comprising a tube which in the direction of its axis constitutes the long arm of the lever; the valve engaging end of said arm being adapted to engage the valve at any point in its circumference, and having a rim of enlarged thickness for said engagement.
25. A trap having, in combination with a valve and an expansion member, a lever intervening, comprising a tube which in the direction of its axis constitutes the long arm of the lever and a plug in which is the fulcrum; the said plug engaging said tube longitudinally with a screw thread and

transversely with a shoulder fitting across the end of the walls of the tube.

26. A trap having, in combination with a valve and an expansion member, a lever intervening, comprising a tube which in the direction of its axis constitutes the long arm of the lever and a plug in which is the fulcrum; the said plug engaging said tube longitudinally with a screw thread and transversely with a shoulder fitting across the end of the walls of the tube; the said plug having parallel grooves in its opposite ends in planes close together, for making the short arm of the lever.
27. A trap having, in combination with a valve and an expansion member, a lever intervening, comprising a tube which in the direction of its axis constitutes the long arm of the lever and a plug for the tube end, in which plug are two parallel grooves, one on the inside for receiving the power of the expansion post, and the other on the outside for receiving the fulcrum.
28. A trap having, in combination with a valve and an expansion member, a lever intervening, comprising a tube which in the direction of its axis constitutes the long arm of the lever and a plug for the tube end, in which plug are two parallel grooves, one diametrically arranged on the inside and receiving the power, and the other on the out-

side, offset from the diametrical plane the distance of the short arm of the lever for receiving the fulcrum.

29. A trap having in combination a valve, an expansion member, and a lever intervening; the expansion member being a post having pivotal support at its end remote from the lever whereon it may swing to permit substitution of levers having short arms of various lengths.

30. A trap, having in combination a valve; an expansion member; a lever intervening, comprising a tube which in the direction of its axis constitutes the long arm of the lever and a plug in the tube having points of engagement for the fulcrum and for the expansion member; and a tubular casing for the whole holding the fulcrum in the plane of its axis; the expansion member being cylindrical and having a pivotal support at one end on the casing and at its other end having a knife edge engagement with the lever in the plane of its own axis and of the axis of the lever tube; whereby the expansion member and the lever can fit together at various angles according to various lengths of short arm therefrom to the plane of engagement of the fulcrum with the lever.

Signed at Providence this nineteenth day of July, 1919. 60

WILLIAM J. TURNER.
